UNITED STATES PATENT OFFICE.

WALTER P. WEBBER, OF LYNN, MASSACHUSETTS.

NECKTIE HOLDER.

Application filed January 10, 1928. Serial No. 245,743.

My invention relates to necktie holders of the type adaptable to wear about the neck. It has for its objects to make it possible to put on, wear, and remove neckties without 5 tying or untying the same after the tie has once been properly adjusted; to thereby increase the wearing life of a tie; to make it possible to change ties without removing the collar; and to provide the various other advantages and results made evident from the following specification.

I accomplish the objects of my invention as shown in the accompanying drawings which form a part of this specification and 15 in which Figure 1 shows perspective view of my device. Figure 2 shows a cross sectional view on the line A—A in Figure 1. Figure 3 shows my device in use. Referring again to the figures, B shows the band portion of 20 my device, which is narrowed from the bottom to the top at its center portion C, its top line being continuously straight. The holding fingers D and E depend from opposite sides of the band B and are doubled over 25 upon themselves to form hooks, the terminals of which are incident to or below the bottom edge of the band and face inwardly so as to form an effective grip on the under side of the inner portion of the collar. The ends of 30 the fingers D and E are crimped at F and G, and H and I, so as to increase their gripping power. The straight line top maintains the position of the tie near the top of the collar as shown in Figure 3. A changing of 35 the straight line from the top to the bottom and a narrowing of the band from the top to the bottom may optionally be had and results in the tie shown in Figure 3 being fixed in a lowered position.

My device is preferably made from thin 40 gage spring steel shaped as shown in Figure 1, but any other suitable material may as well be used. It is also preferably made from a single continuous sheet. The device is adaptable for four in hand, bow and ribbon ties, 45 fits turn down collars, starched, or semi-soft, and effectively holds the tie in place.

While I have illustrated and described a preferred construction for carrying my invention into effect, this is capable of variation or modification without departing from the spirit of the invention. I therefore do not wish to be limited to the exact details of construction herein set forth but desire to avail myself of such variations and modifications as come within the scope of the appended claim.

Having thus described my invention I claim as new and desire to secure by Letters Patent of the United States of America:—

A neck tie holder comprising a spring metal tie holding band, the ends of which are spaced apart so that the band may be inserted in a collar with the ends extending about the sides of the collar toward but not across the 65 back of the collar, a portion of the lower edge of the band on each side of the center point thereof being cut away toward the top edge of the band to provide a relatively narrow section, and depending members near the ends 70 of the band bent inwardly upon themselves to provide hooks the terminals of which are incident to or below the lower edge of the band to engage the inner portion of the collar; the top edge of the band being relatively 75 straight.

In testimony whereof I affix my signature.
WALTER P. WEBBER.
